UNITED STATES PATENT OFFICE

168,061

FORK

John C. Moore, Los Angeles, Calif.

Application November 13, 1951, Serial No. 17,360

Term of patent 14 years

(Cl. D44—29)

To all whom it may concern:

Be it known that I, John C. Moore, a citizen of the United States of America, residing at Los Angeles, in the county of Los Angeles, State of California, have invented a new, original, and ornamental Design for a Fork, of which the following is a specification, reference being had to the accompanying drawing, forming a part hereof.

Figure 1 is a perspective view of a fork, showing my new design;

Figure 2 is a top plan view of the fork of Figure 1;

Figure 3 is a front elevational view thereof;

Figure 4 is a left side elevational view thereof;

Figure 5 is a bottom plan view thereof; and

Figure 6 is a fragmentary right side elevational view as seen from the direction of the arrow in Figure 3.

I claim:

The ornamental design for a fork, as shown.
JOHN C. MOORE.
